UNITED STATES PATENT OFFICE.

JAMES J. WADE, OF CHICAGO, ILLINOIS.

DRAINAGE AND SEWER SANITARY APPLIANCE.

No. 832,710.

Specification of Letters Patent.

Patented Oct. 9, 1906.

Application filed April 17, 1905. Serial No. 256,137.

To all whom it may concern:

Be it known that I, JAMES J. WADE, a citizen of the United States of America, and a resident of Chicago, Cook county, Illinois, have invented a certain new and useful Improvement in Drainage and Sewer Sanitary Appliances, of which the following is a specification.

My invention contemplates certain improvements in the connections, joints, appliances, &c., employed in connecting sinks, closets, drain-pipes, and the like with sewers and other main offtakes.

Objects of my invention are to provide an improved flush-out adapted for use in all places where it is necessary or desirable to occasionally flush the interior of a pipe, catch-basin, trap, or the like for the purpose of keeping the same in cleanly and sanitary order; to provide an improved closet connection of such character as to facilitate the establishment of connection between a closet and the pipe leading to a sewer; to provide an improved construction by which a casting—such, for example, as a back-water gate-valve—may be provided with a threaded boss adapted to receive the threaded end of a pipe without the necessity of turning the threads in the metal of the casting; to provide an improved pipe-coupling for appliances such, for example, as a catch-basin and whereby either a threaded or a calked joint may be established, according to whether the pipe is threaded or unthreaded; to provide an improved straightway clean-out for offtakes or outlets—such, for example, as the interior elbow-shaped offtake-pipe of a catch-basin—and to provide certain details and features of improvement tending to increase the general efficiency of devices of this particular nature.

To the foregoing and other useful ends my invention consists in matters hereinafter set forth and claimed.

In the accompanying drawings, Figure 1 shows a "back-water gate-valve" equipped with my improved flush-out and threaded boss or bushing. Fig. 2 is a section on line 2 2 in Fig. 1. Fig. 3 shows a "catch-basin" equipped with my improved flush-out, pipe-coupling, and straightway clean-out for the offtake or outlet. Fig. 4 is a section on line 4 4 in Fig. 3. Fig. 5 is a section on line 5 5 in Fig. 4. Fig. 6 shows a "floor-drain" equipped with my improved flush-out. Fig. 7 is a section on line 7 7 in Fig. 6. Fig. 8

shows a "closet connection" provided with my improved flush-out and calked joint. Fig. 9 is a section on line 9 9 in Fig. 8. Fig. 10 shows a "grease-trap" constructed with my improved flush-out. Fig. 11 is a section on line 11 11 in Fig. 10. Fig. 12 shows a "drum-trap" equipped with my improved flush-out. Fig. 13 is a section on line 13 13 in Fig. 12. Fig. 14 is a section on line 14 14 in Fig. 3. 65

The back-water gate-valve A (shown in Figs. 1 and 2) comprises the usual inlet *a* and the outlet *a'* and the swinging valve member *a*², the latter adapted to prevent a backflow from the sewer. In addition, however, the structure is provided with the novel feature of a divided flush-out consisting of two water-inlet openings *a*³, the same being adapted to discharge two converging streams or jets against the opposite sides of the interior and in such manner that the two jets rebound and come together, causing a very efficient flushing action. A flushing-pipe *a*⁴ leads to the said flush-out and is secured in place by means of a threaded bushing *a*⁵, secured in place during the process of casting—that is, the metal is cast around its outer threaded surface. In this way a cheap but entirely satisfactory threaded joint is obtained without the necessity of cutting or turning threads in the metal of the casting, for I find it cheaper and more satisfactory to buy internally and externally threaded bushings and cast the metal around them than to cut the threads directly in the metal of the casting. 70 75 80 85 90

The divided flush-out insures a highly efficient scouring or cleaning action of the water. In Figs. 3, 4, 5, and 14 the catch-basin B is provided with a similar flush-out consisting of the inlet-openings *b*, to which water is conducted by the pipe *b'*. Also the structure is provided with an improved pipe-coupling *b*² for the intake-pipe. Said coupling has a threaded portion *b*³ for threaded pipes and a non-threaded portion *b*⁴ for smooth or unthreaded pipes, the internal diameter of the internally-threaded portion being less than the internal diameter of the non-threaded portion. In this way a threaded joint can be made with a threaded pipe and a calked joint with an unthreaded pipe, the one coupling or fitting answering for both cases. Furthermore, the said catch-basin has the regular elbow-shaped internal offtake *b*⁵; but in accordance with my invention said offtake has its elbow provided with a straightway clean-out device *b*⁶. This clean-out 100 105 110

preferably consists of a swinging valve member adapted to normally close the opening in the elbow and held in place by a thumb-screw b^7 . When it is desired to "rod-out" 5 the passage, the cover b^8 can be removed and the thumb-screw b^7 loosened for the purpose of opening the elbow—that is, so as to create a straight way from the intake b^9 to the off-take b^{10} , and thereby facilitate "rodding-out." This elbow-shaped offtake is also provided with a divided flush-out consisting 10 of the divergent openings b^{11} and b^{12} . The opening b^{11} discharges a jet of water across the upper or horizontal portion of the elbow-shaped offtake and toward the offtake b^{10} ; but the opening b^{12} discharges a jet of water across and downwardly of the vertical portion of the said elbow-shaped member. With 15 this provision the offtake means can be flushed and thoroughly cleaned. A flushing-pipe b^{13} conducts the water to the openings b^{11} and b^{12} .

In Figs. 6 and 7 the floor-drain C is provided with a surface intake c and an offtake c' . A trap or water seal c^2 is also provided, 25 as well as a back-water gate-valve device c^3 . Between the trap and the swinging valve member the floor-drain is provided with my improved flush-out, consisting of two divergent inlet-openings c^4 , connected to receive water from the flushing-pipe c^5 . With this 30 provision the valve can be effectually flushed and cleared of all accumulations.

In Figs. 8 and 9 the closet connection D has my improved flush-out, consisting of the flaring or divergent openings d , arranged to receive water from the flushing-pipe d' . Another feature of novelty consists of a thimble d^2 , provided with a flanged bushing d^3 . With 35 this arrangement the connection D can be adjusted into place, and if it is not level the thimble d^2 can be tilted or raised at either side for the purpose of making it level. The seat d^4 provides a somewhat loose joint between the thimble and connection, thus making it easy to level up the flange d^5 and connect the same with the closet regardless of the exactness with which the connection D is connected with the pipe leading to the sewer. 40 The joint between the thimble and connection D can be calked tight in the usual manner.

In Figs. 10 and 11 the grease-trap E can be constructed in the ordinary manner, with 45 the exception, however, that the side of the trap is provided with my improved flush-out, consisting of the flaring or divergent openings e , arranged to receive water from the flushing-pipe e' .

In Figs. 12 and 13 the well-known drum-trap F is provided at its side and near its bottom with my improved flush-out, consisting of the divergent openings f , arranged to receive water from the flushing-pipe f' .

It is evident that my improved flush-out is

applicable to a great variety of sanitary appliances. The flush-out is always arranged, it will be seen, so as to send the two divergent jets of water forward in the chamber or passage to be flushed, one jet at each side thereof, thus producing the desired and improved swirling or flushing action of the water therein. The additional or auxiliary flush-out, 70 consisting of the two jet-openings b^{11} and b^{12} , does not, of course, have the characteristics 75 of the main flush-out—that is to say, does not have its two jet-openings in the same horizontal plane. As stated, however, the main flush-out is always, as shown, so disposed that the jets are directed in a forward direction, one at each side of the chamber to be flushed. For example, in Fig. 3 the chamber B has a horizontal intake and a horizontal offtake and has a flush-out consisting of the pair of divergent jet-openings b , adapted 80 to send two divergent jets of water forward in said chamber, one jet of water at each side thereof. Also in Fig. 3 it will be seen that these two divergent jets of water are projected forward in the direction of the swinging valve member b^6 . This is also true of course of Fig. 1, in which the chamber has a horizontal intake and a horizontal offtake, a swinging valve member a^2 , and a pair of divergent jet-openings a^3 , adapted to project 85 the flushing-jets forward in the direction of the valve member, one jet at each side of the chamber or passage to be flushed. By the expression "forward in said chamber or passage" I mean that the two divergent jets of 90 the flush-out are projected in the same and a more or less horizontal direction—as, for example, in Fig. 1—or in a horizontal direction—as, for example, in Fig. 12—and that preferably this general direction is toward the offtake, as is true, of course, of Figs. 1 to 13, inclusive.

It will be seen that in Figs. 1 to 13, inclusive, the jet-openings are formed in and lead through the wall of the passage or chamber to be flushed and that the entire flush-out is outside of said passage or chamber. It will be understood, however, that I do not limit myself to any particular means for supplying water to the outer or converging ends of the 100 jet-openings of the flush-out leading through the wall of the passage or chamber to be flushed.

What I claim as my invention is—

1. A flush-out for devices of the character 110 described, comprising a pair of divergent jet-openings b adapted to discharge the water in two divergent jets or streams, and a flushing-pipe b' connected to supply water to said jet-openings, an intake and an offtake for the 115 means having said flush-out, and a swinging valve member in alignment with said intake and offtake and providing a straightway 120 clean-out, said offtake having vertical and horizontal portions with the said valve mem- 130

ber applied to its elbow, substantially as and for the purpose set forth.

2. A flush-out for devices of the character described, comprising a pair of divergent jet-openings *b* adapted to discharge the water in two divergent jets or streams, a flushing-pipe *b'* connected to supply water to said jet-openings, and an elbow-shaped offtake for the means having said flush-out, together with
- 5 an additional flush-out for said offtake, adapted to discharge the water outwardly and also downwardly therein, substantially as and for the purpose set forth.
3. In a catch-basin, an intake and an off-take, the offtake being provided with a vertical inlet portion and a horizontal outlet portion, the intake and said outlet portion being in alinement, and a normally closed straightway clean-out applied to the elbow
- 15 portion of said offtake, said clean-out being in alinement with the said intake and outlet portion, substantially as and for the purpose set forth.
4. In a catch-basin, an elbow-shaped off-take provided with a flush-out adapted to
- 20
- 25

discharge water both outwardly and downwardly therein, substantially as and for the purpose set forth.

5. In a device of the class specified, the combination of a passage or chamber to be flushed at will, an intake and an offtake therefor, and a flush-out consisting of a pair of divergent jet-openings formed in and leading through the wall of said passage or chamber and adapted to send two divergent jets of water forward in said chamber or passage, one jet at each side thereof, together with a socket formed in the outside of said wall and communicating with the converging ends of said jet-openings, and a flush-pipe secured in said socket, said flush-out being entirely outside of said passage or chamber, substantially as set forth.

Signed by me at Chicago, Illinois, this 12th day of April, 1905.

JAMES J. WADE.
